UNITED STATES PATENT OFFICE.

HILAND W. GOODWIN, OF MUIR, ASSIGNOR TO HIMSELF AND SAMUEL J. BROMLEY AND HENRY POTTER, BOTH OF BATTLE CREEK, MICHIGAN.

LIFTING-JACK.

SPECIFICATION forming part of Letters Patent No. 244,587, dated July 19, 1881.

Application filed June 14, 1881. (No model.)

To all whom it may concern:

Be it known that I, HILAND W. GOODWIN, a citizen of the United States of America, residing at Muir, in the county of Ionia and State 5 of Michigan, have invented certain new and useful Improvements in Lifting-Jacks; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 This invention has relation to improvements in lifting-jacks; and it consists in the novel construction and arrangement of the various parts of which its composed, whereby the lifting of heavy weights may be easily accomplished with but little exertion by the operator; and it also consists in a locking device applied thereto to prevent accidents, all of which will be hereinafter more fully explained.

20 The annexed drawings, to which reference is made, fully illustrate my invention, in which—

Figure 1 represents a vertical sectional view of my improved lifting-jack. Fig. 2 represents a top or plan view of the same, and Fig. 3 represents a detail view of the locking device.

30 The letter A designates the base of the jack, having secured thereto and arising therefrom four standards, *a a a*, between which and on all sides of the jack are spaces *a' a' a'*.

B designates the vertically-adjustable post, 35 which is forked at *b*, below the middle portion, thereby forming a slot, *b'*, which is provided at its upper or closed end with a roller, *b²*, and at its lower or open end with a pin, *b³*, running crosswise the same. Said post is solid from 40 the middle portion to the top, and is provided with projections *b⁴ b⁴ b⁴ b⁴* on each side thereof, and a spring catch or lock, *b⁵*, that has in its lower and free end a perforation, *b⁶*, while the upper end is secured at *b'* to the face of the 45 post aforesaid.

C indicates the operating-lever, constructed with a semicircular enlargement, *c*, and is provided with a pin, *c'*, on its outer face, and on its under side with a rod, *c²*, that passes 50 through staples or eyes *c³ c³ c³* secured to said lever. The outer end, *c⁴*, of said rod is bent in

hook-form, while the opposite end is bent into a loop or handle, *c⁵*. Said rod is also provided with a spring, *c⁶*, for operating the same.

Having thus given a description of the different parts of which my improved lifting-jack is composed, I will now proceed and explain the manner in which it is operated in raising and lowering weights and locking the parts to one another when the jack is in use. 60

Fig. 1 of the drawings represents the post B in a raised position, with the outer end of the lever C lowered, and the roller with the post resting upon and being supported by the semicircular enlargement or head *c* at the same time the pin *c'* is connected to and projecting through the perforation *b⁶* in the spring catch or lock *b⁵*, thereby securing the post B and lever C to one another. The post in its vertical movement, when operated, slides between the 65 four uprights or standards *a a a a*, and the projections *b⁴ b⁴ b⁴ b⁴* on its sides slide within the spaces *a' a' a' a'* formed between the standards aforesaid, which latter are connected by a band, 70 *d*, encircling the top of the jack. 75

In releasing the jack or the post B from the weight the operator simply grasps the lever C by the handle, and with one finger through the loop or handle *c⁵* of the rod *c²* gives the latter a gentle forward movement, which causes the hook end *c⁴* of said rod to strike against the lower end of the spring catch or lock *b⁵*, thereby forcing the latter outwardly and releasing the same from engagement with the pin *c'* on the head or enlargement of the lever C, thus 80 allowing said lever to be raised, thereby lowering the post B by means of the roller *b²* traveling upon the cam or head *c*, after which the rod *c²* has a reverse movement by means of the spring *c⁶* encircling the same, and having one end bearing against one of the staples *c³* and the opposite end attached to the loop of the rod aforesaid. Should a second stroke be needed in raising the post B to a desired height, the lever C is to be slightly raised and given a forward movement, thus withdrawing the side pins, *d' d'*, on the head or cam *c* from engagement with the notch *d²*. At the same time said pins enter a vertical slot, *d³*, made on the inner face, and communicating with the mouth 90 of each of the notches *d²*. The lever is then raised until the pins *d' d'* drop within another 95

and higher notch, thereby allowing the post to be raised so much higher—the distance from one notch to another—in addition to that caused by the cam or head *c*. Any number of 5 notches, *d*², may be formed on the post to suit different heights.

A stop-pin, *d*⁴, may be placed on each side of the lever *C* to regulate the downward movement of said lever by means of the pins afore- 10 said striking against the standards *a a*, thereby preventing the lever falling too low.

It will thus be seen by the foregoing description that in constructing my lifting-jack I attach a locking device to the post *B* in the 15 shape of a flat spring. Said spring, having the perforation, connects with the pin automatically on the lever, and secures by said connection the lever and post to one another, thereby preventing any accidents which are liable 20 to happen in operating this kind of lifting-jack. Again, it will be observed that by my construction of a jack with four standards, and placing in the center thereof the post *B*, I am enabled to obtain a center and direct lift to 25 the post, and at the same time it is easily operated, simple in construction, and cheap to manufacture.

Having described this invention, what I desire to secure by Letters Patent is—

1. In a lifting-jack, the combination of the 30 adjustable post *B*, having projections *b*¹, and forked end *b*, and provided with the roller *b*², with the standards *a*, secured to the base *A*, and the lever *C* operating therewith, as shown, described, and for the purpose set forth. 35

2. In a lifting-jack, the spring catch or lock *b*³, secured to the post *B*, and having a perforation, *b*⁶, in its free end for engagement with the pin *c*' on the lever *C*, whereby said lever and the post are locked to one another, as 40 shown, described, and for the purpose specified.

3. In a lifting-jack, the spring catch or lock *b*³, secured to the post *B*, operating automatically with the pin *c*', the rod *c*², provided with the spring *c*⁶ for operating the same, in combination with the standards *a a a a*, post *B*, roller *b*², and lever *C*, as shown, described, and for the purpose specified. 45

In testimony whereof I affix my signature in presence of two witnesses.

HILAND W. GOODWIN.
